UNITED STATES PATENT OFFICE.

JAMES M. CORBOY, OF EDGEWOOD PARK, PENNSYLVANIA.

FILING SYSTEM.

No. 853,864.

Specification of Letters Patent.

Patented May 14, 1907.

Application filed April 12, 1906. Serial No. 311,340.

To all whom it may concern:

Be it known that I, JAMES M. CORBOY, a citizen of the United States, residing at Edge-
wood Park, in the county of Allegheny and
5 State of Pennsylvania, have invented certain
new and useful Improvements in Filing Sys-
tems, of which the following is a specification,
reference being had therein to the accom-
panying drawings.

10 My invention comprises an improved filing
system for papers, etc. and it has for its ob-
jects to entirely eliminate the necessity of
any of the usual indexes or other guides for
the purpose of finding any previously sorted
15 or located matter, the system involving the
use of a continuous series of holding files
adapted to contain all of the papers com-
prised in each separate piece of business or
transaction, so arranged and located with
20 reference to each other, and within the con-
trolling limitations of the system, that each
particular file may be readily located.

In addition to the elimination of any extra
25 index guide or other device intended to
locate the particular file, each file in itself
provides all of the necessary data and infor-
mation as to entries, etc. as well as the in-
closed contents of the file, while embodying
30 in itself the features and elements which
co-operate with the entire system, comprising
all of the files, for the objects in view.

Referring to the drawings:—Figure 1. is a
view in front elevation of a complete cabinet
35 of drawers comprising my entire system of
files. Fig. 2. is a perspective view of one of
the drawers or file-holding boxes, illustrating
the use of the system. Fig. 3. is a similar
40 view of one of the individual files showing the
marginal index letters and illustrating the
manner in which the face of the file is utilized
for making inscriptions, notations, etc.

In carrying out my invention I employ
what I call the "vowel and consonant sys-
tem" and have devised a division of the al-
45 phabet whereby, as nearly as possible, an av-
erage number of files will be located in each
separate drawer or compartment of the cabi-
net, each of said drawers or compartments
50 being adapted to contain all of the files of the
system within the limitations of certain pre-
determined vowels and consonants, occur-
ring in the name by which the file is identi-
fied.

The system is entirely independent of the
55 initial letter of the name and is designed to
assemble all names controlled, for instance

by the second and third letters of the name,
each file itself being provided with a marginal
row of the letters of the alphabet with which is
incorporated an attachable tab for facilitat-
ing the finding of the particular name sought
for.

An especial advantage of my improved
system is that each file is set upon edge so as
to expose its particular tab to view without
the necessity of moving any of the other files.

Various other features of advantage and
improvement will be more fully hereinafter
described.

Referring now to the drawings, 2 repre-
sents the filing cabinet of any suitable con-
struction in which are arranged a series of
drawers or compartments 3, more clearly
shown in Fig. 2. Each drawer is of suitable
size to receive the series of files as shown in
75 Fig. 3 and adapted to contain all of the con-
tents, as for instance correspondence, memo-
randa, etc. of the business identified by the
name of the party, as the name John Logan.

Each particular folder or file is provided
80 along its upper front edge with initial letters
comprising all of the letters of the alphabet
from A to Z, as clearly shown in Fig. 3, and
for the purpose of identifying the particular
name in any of the several series of files I em-
ploy an attachable tab 4 which is pasted
85 upon the file at its upper edge corresponding
with the particular letter, as the letter "L"
in the example used.

Under the vowel and consonant system 90
which I have devised the location of each
particular file will not be controlled by the
initial letter "L" but by the second and
third letters "O," "G," and in searching for
such file it will be found in that drawer or
95 compartment in which the range of letters
would include such a combination, said
drawer being the third drawer to the right in
the third row from the top identified by the
letters O A to O L. Likewise, all files in
100 which the name, (whatever it may be irre-
spective to its initial letter,) contains a sec-
ond and third letter falling within this arbi-
trary range, will correspondingly be found in
the same compartment.

105 This feature of the invention is clearly illus-
trated in Fig. 2 of the drawings, and it will be
seen that the proper compartment having
been selected and the name being searched
for in its proper position with relation to the
110 initial letter, it may be at once readily lo-
cated and removed. The reason for this is

that the various files are so thoroughly mixed with regard to the initial letter, that any particular initial letter sought for in its particular place will be readily found without confusion with other conflicting or similar names, or with a large class of names commencing with the same initial.

The exterior of the folder is employed, as shown, for the making of indorsements, notes, memoranda or entries of any suitable kind, and it will be understood that any desired arrangement of spaces or blanks may be employed to suit the particular business.

The advantages of the system will be readily understood and appreciated by all those accustomed to the keeping of accounts in files; it may be employed either with or without additional calendar or other intervening files; it entirely obviates the necessity of any preliminary index; and results in an even distribution of the file folders due to the particular combinations of the vowels and consonants employed. This latter feature is the result of several years experience in the keeping of records by files and will be found to be approximately correct as to the distribution of the subject matter in any predetermined space, based on the law of average of names.

While the arrangement and distribution of vowels and consonants as shown will be found entirely practicable and satisfactory for a sixteen drawer file, it will be understood that the system may be condensed into any less number or expanded into a greater number, care being taken to observe the proper ratio. Thus for instance, in an eight drawer system the range for the first drawer would be AA to ARZ. In a four drawer system the range for the first drawer would be AA to EE. Likewise in a thirty two drawer system the inclusive range of the first and second drawers would be AA to AM, the first drawer including AA to AG and the second including AH

to AM respectively. Other proportional arrangements or divisions may be made to suit different requirements or circumstances.

Having described my invention, what I claim is.

1. An improved filing system comprising a plurality of compartments characterized by predetermined vowel and consonant limit identifications with relation to the consecutive letters of a word or name independent of its initial letter, and a series of files having name identifying devices in definite positions with relation to the initial letter of the word or name, substantially as set forth.

2. An improved filing system comprising a plurality of compartments characterized by predetermined vowel and consonant limit identifications with relation to the consecutive letters of a word or name independent of its initial letter, and a series of files each having a series of initial letters adapted to co-operate with an identifying name device, substantially as set forth.

3. An improved filing system comprising a plurality of compartments identified by predetermined vowel and consonant limit identifications, and a series of files each provided with series of initial letters, and name devices appropriately attached thereto, substantially as set forth.

4. A double filing folder having its upper edge provided with series of initial letters, a name device appropriately attached thereto, and having its face provided with suitable data for entries, etc., substantially as set forth.

In testimony whereof I affix my signature in presence of two witnesses.

JAMES M. CORBOY.
